UNITED STATES PATENT OFFICE

2,003,179

MAGNETIC COMPASS

Harold T. Faus, Lynn, Mass., assignor to General
Electric Company, a corporation of New York

Application October 12, 1933, Serial No. 693,279

8 Claims. (CL 33—222)

My invention relates to magnetic compasses and orienting devices and has for its principal object the provision of compasses of increased sensitiveness and decreased tendency toward vibration. Other and further objects and advantages will become apparent as the description proceeds.

In carrying out my invention in its preferred form, I utilize one or more composite bars of magnetic material as the magnetic directing element. The composite bars comprise a central portion of high permeability material and end portions of high coercive force material. In this manner, the magnetic leakage flux is concentrated at the ends of the composite bars and the central portions of the bars are easily machinable to permit mounting of jewels or bearings for pivoting. The compasses are preferably mounted in cups of electrically conducting material coaxial with the pivot axis for the purpose of damping vibrations by the absorption of the energy of vibration as eddy currents in the electrically conducting material.

The features of my invention which I believe to be novel and patentable will be pointed out in the claims appended hereto. A better understanding of my invention, itself, may be obtained by referring to the following description taken in connection with the accompanying drawing in which Fig. 1 is a plan view of one embodiment of my invention; Fig. 2 is an elevation, partially in section, of the embodiment of Fig. 1; Fig. 3 is a plan view of the rotatable element in a modified form of my invention; Fig. 4 is a schematic circuit diagram illustrating the application of compasses made in accordance with my invention to the automatic steering of vessels; Fig. 5 is an elevation, partially in section, of a portion of the apparatus shown in Fig. 4; and Fig. 6 is a perspective view in part of another modified form of my invention designed to minimize vibration around a horizontal axis as well as around the vertical axis.

Referring now more in detail to the drawing in which like reference characters are used to designate like parts throughout, in the arrangement illustrated in Figs. 1 and 2, a magnetic compass is mounted in a suitable case 11 having a suitable protective cover 12, preferably composed of glass or other transparent material. The directing element, itself, comprises a composite bar 13 consisting of a central portion 14 carrying magnetic bars 15. The bars 15 are composed of magnetic material having a high coercive force, such as, for example, cobalt steel containing ap-

proximately 46% cobalt, or a steel alloy containing approximately 6 to 15% aluminum, 20 to 30% nickel, and, in some cases, a certain amount of chromium in addition to iron. Such alloys may be prepared with coercive forces varying from 5 300 to 500 Gilberts per centimeter and even much higher. The central portion 14 is composed of magnetic material having a high permeability, for example, an alloy of nickel and iron containing approximately 78½% of nickel. This material not only has high magnetic permeability but is relatively easily machined in comparison with any material which would be suitable for permanent magnets. For this reason, the expense of manufacture of the compasses is considerably reduced since it is unnecessary to drill 10 into hard steel for the purpose of mounting jewels or bearings or, in the alternative, it is unnecessary to go through the double process of machining the compass needles before hardening them, 15 and then hardening them after the machining operation has been completed. By employing a material of high permeability for the central portion, only a small portion of the magnetizing force of the high coercive force end portions is 20 required to keep the flux density in the central portion as high or higher than that in the end portions. In this manner, the composite needle acts as a single long magnet with the correspondingly low demagnetizing effect and high magnetic moment. Likewise, the leakage flux is concentrated in the ends of the composite compass needle and increases the damping effect when the needle is placed inside a ring of copper as will be explained hereinafter.

In the arrangement shown in Figs. 1 and 2, the high permeability pieces 14 are provided at their outer ends with transverse projections 16, which may be bent up to grip the inner ends of the magnetized bars 15. If desired, the portions 30 16 may be so proportioned as to permit completely surrounding the bar 15 and, if desired, they may be increased somewhat in length to form tubular portions 17 receiving the bars 15, as shown in Fig. 6, in order to minimize leakage 35 or stray flux. The central portion 14 is pierced to form a circular opening 18 in which may be mounted a hollow cylindrical piece 19 carrying a jewel 20, or other suitable bearing, to cooperate with a conical pivot 21. The hollow cylindrical piece 19 also carries a pointer 22 cooperating with a scale 23, the graduations of which are not shown but which may be divided in degrees or in accordance with the well-known 40 points of the compass.

Although I have disclosed in Figs. 1 and 2 an arrangement in which a separate pointer is employed and the magnetic element is mounted on a pivot, it will be understood that I am not limited to this exact arrangement. If desired, for example, a compass card of the type shown in Fig. 3 may be utilized instead of the pointer 22, or the composite bar 13, itself, may serve as the pointer. Likewise, any other desired rotatable mounting may be employed, such as, for example, floating a movable element 13 with a card of the type shown in Fig. 3 in alcohol or other suitable fluid contained in a cup 24.

In order to minimize vibrations, the composite magnetic needle 13 is preferably mounted within a cup 24, composed of electrically conducting material, substantially coaxial with the pivot 21 or the axis of rotation of the composite needle 13. As it will be readily understood by those skilled in the art, if the element 13 vibrates or oscillates about the pivot 21, the magnetic flux produced by the magnetized bars 15 will cut through portions of the metal of which the cup 24 is composed, inducing electromotive forces therein which tend to produce eddy currents. The eddy currents in turn produce magnetic flux which reacts with the magnetized bars 15 to oppose the oscillatory motion of the needle 13, and the energy of oscillation is rapidly absorbed or dissipated by the eddy currents in the cup 24. In this manner, oscillation of the magnetic needle 13 is retarded. By means of this construction, I have succeeded in producing compasses which make not more than one and one-half complete vibrations after being deflected 90° and released. The reaction between the magnets 13 and the damping element 24 obviously overcomes oscillation about a horizontal axis transverse to the composite needle 13, as well as about the vertical axis of the pivot 21. Although, in the arrangement shown in Fig. 2, I have disclosed damping element 24 in the shape of a cup, it will be understood that a damping ring, which in the lower portion 25 is omitted, might also, if desired, be employed.

In the arrangement shown in Figs. 1 and 2, I have illustrated the use of a single composite magnetic needle 13, but it will be understood that my invention is also applicable to magnetic compasses and orienting devices in which a plurality of magnetic needles are employed. For example, in the arrangement of Fig. 3, a plurality of composite needles 13' are mounted on a compass card 26. In the arrangement of Fig. 6, a plurality of magnetized bars 15 are mounted in a central element 14 composed of high permeability material which may, if desired, be in sheet form with lateral projecting portions rolled to form hollow cylindrical portions 17 to receive the inner ends of the magnetized bars 15. It will be understood that the directing element, comprising a high permeability portion 14 and the magnetized bars 15, will be mounted in a suitable manner, such as, for example, by means of a cylindrical sleeve and bearing of the type shown at 19 and 20 in Fig. 2. As already explained, the eddy currents produced in the conducting ring 14 tend to dampen and overcome the vibrations of the rotatable element about its pivot axis or axis of rotation 21, 21' and its transverse horizontal axis T, T'. However, by employing a plurality of composite magnetic needles as shown in the arrangements of Figs. 3 and 6, I am also able to dampen vibrations about a longitudinal horizontal axis, such as the axis

27, 27' or about the axis of one of the bars 15. In the case of delicately balanced card compasses, particularly, this will obviously be advantageous.

In addition to direction indicating devices or compasses, my invention may also be applied to other apparatus employing direction responsive elements. For example, in the automatic steering apparatus disclosed in Figs. 4 and 5, a magnetic compass, constructed in accordance with my invention, is mounted on a ship or on aircraft so that the deflecting pointer 22 is permitted to cooperate with a pair of contacts 28 and 29 carried by a rotatable mounting 30, which may be adjusted in angular position with respect to the fore and aft line of the ship or aircraft by means of any suitable device, such as the worm gear 31. The deflecting element 22 is arranged to control either directly or indirectly through contact 28 or 29 a steering motor 32 having a pair of oppositely connected field windings 33 and 34. Direct current is supplied by source 35 and the steering motor 32 is mechanically connected through gearing 36 to a lever 37 connected to a rudder not shown.

The rotatable mounting 30 is rotated so that the fore and aft line 38, 38' of the vessel bears the desired angular relationship to the magnetic north-and-south line 39, 39' on the rotatable mounting 30. The line 39, 39' is obviously a magnetic north-and-south line since, whenever the vessel veers from its course, the deflecting pointer 22 makes contact with one or the other of contacts 28 and 29 so that the steering motor 32 is operated and the course is corrected so as to make the line 39, 39' follow the magnetic north and south. As will be readily understood, when contact is made between pointer 22 and contact 28, the circuit will be closed from the source 35 through conductor 40, pointer 22, contact 28, collector ring 41, field winding 34, conductor 42, back to source 35, starting the operation of steering motor 32 in a given direction. Likewise, when the pointer 22 makes contact with the contact 29, the circuit will be closed from the source 35 through conductor 40, pointer 22, contact 29, collector ring 43, field winding 33, and conductor 42, back to source 35, starting the operation of the steering motor in the opposite direction.

While I have described my invention as embodied in concrete form and as operating in a specific manner in accordance with provisions of the patent statutes, it should be understood that I do not limit my invention thereto since various modifications thereof will suggest themselves to those skilled in the art without departing from the spirit of my invention, the scope of which is set forth in the annexed claims.

What I claim as new and desire to secure by Letters Patent of the United States is:

1. A compass needle comprising a central portion composed of magnetic material and end portions composed of a different magnetic material, the material of which the central portion is composed being softer and more permeable than the material of the end portions, and the material of which the end portions are composed having a higher coercive force than the material of the central portion in order to provide a high directing force for the needle.

2. A compass needle comprising a central portion composed of an alloy comprising iron and 40% to 80% nickel and end portions composed of

an alloy comprising 20 to 30% nickel, 6 to 15% aluminum and the remainder iron, thereby obtaining a relatively easy machinability and high permeability in the central portion and high coercive force in the end portions in order to provide a high directing force.

3. A direction-responsive device comprising a damping ring of current-conducting material and a directing element having a central portion composed of a magnetic material and end portions composed of a different magnetic material, the central portion being adapted to be pivoted about a transverse axis and being composed of a softer and more permeable material than the end portions in order to concentrate the leakage flux in the end portions, the end portions being composed of higher coercive force material than the central portion in order to provide a high directing force for the needle, and said damping ring being coaxial with the pivot axis of and surrounding said directing element for the purpose of damping vibration thereof.

4. An orienting device comprising a center pivoted directing element having a central portion composed of a magnetic material and end portions composed of a different magnetic material, and means actuated by the force of deflection of said member, the material of which said central portion is composed being softer and more permeable than that of the end portions, and the material of which the end portions are composed having higher coercive force than the material of the central portion in order to provide a high directing force for the directing element.

5. An orienting device for a conveyance comprising a magnetic directing element having a middle portion composed of a magnetic material and end portions composed of a different magnetic material, means attached to the middle portion of said directing member for pivoting the same, and means responsive to the deflection of said directing member serving to maintain such conveyance in a predetermined course, the material of which said middle portion is composed being softer and more permeable than that of the end portions, and the material of which the end portions are composed having a higher coercive force than the material of the central portion.

tion in order to provide a high directing force for the directing element.

6. An orienting device comprising a central portion composed of magnetic material in sheet form and end portions composed of a different magnetic material in the form of bars, said central portion being adapted to be pivoted at its center and having lateral projections at its ends bent around the inner ends of said bars, the material of which said central portion is composed being softer and more permeable than that of the end portions, and the material of which the end portions are composed having higher coercive force than the material of the central portion in order to provide a high directing force for the directing element.

7. A direction-responsive device comprising a directing element with a ring composed of electrically conducting material surrounding said directing element, said directing element comprising magnetic material at its central portion and a plurality of pairs of parallel members composed of a different magnetic material at its end portions, the material of which said central portion is composed being softer and more permeable than that of the end portions to concentrate the leakage flux in the end portions, said members constituting the end portions being in contact at their inner ends with said permeable material and being composed of a material having a higher coercive force than said central portion to provide a high directing force for the directing element, said directing element being adapted to be rotatable about a pivoted axis coaxial with said ring, whereby vibrations of said directing element are damped with respect to rotation about said pivoted axis and also with respect to rotation about the longitudinal axis of said directing element.

8. A compass needle comprising a central portion composed of a magnetic material and end portions composed of a different magnetic material, the central portion being softer and more permeable than the end portions, and the end portions being composed of a material having a coercive force exceeding 300 Gilberts per centimeter in order to provide a high directing force for the needle.

HAROLD T. FAUS.
